UNITED STATES PATENT OFFICE.

DANIEL W. GAGE, OF CAMBRIDGE, MASSACHUSETTS, ASSIGNOR TO J. C. HAWKINS, OF NEWTON, IOWA.

PAPER-FASTENER.

1,130,589.

Specification of Letters Patent.

Patented Mar. 2, 1915.

Application filed May 11, 1910. Serial No. 560,611.

To all whom it may concern:

Be it known that I, DANIEL W. GAGE, of Cambridge, in the county of Middlesex, and State of Massachusetts, have invented certain new and useful Improvements in Paper-Fasteners, of which the following is a specification.

This invention relates to an implement or machine for fastening sheets of paper securely together by means of a part of the paper itself, and without requiring the use of additional means such as metallic clips, eyelets, or the like.

My object is to provide a simple machine or device in the form of an implement which can be held and operated in one hand, and is capable in one operation, during which its moving parts or jaws close together and separate, of cutting a tongue from the material of two or more sheets of paper and of drawing said tongue through the sheets.

In the accompanying drawings I have illustrated one possible embodiment of an implement designed and capable of carrying the objects of my invention into effect.

Figure 1 represents a sectional view of the implement in open position. Fig. 2 is a similar view, showing the implement in closed position. Fig. 3 is a view showing the character of work performed by the implement, the same representing two sheets of paper after having been acted upon, showing a tongue cut from one part of the sheets and tucked through a slit formed in an adjacent part of the sheets. Fig. 4 is a sectional view of the fastening taken on line 4-4 of Fig. 3.

The same reference characters indicate the same parts in all the figures.

One concrete form in which I have embodied the invention is represented in the accompanying drawings for the purpose of illustration, and is hereinafter described in detail for the same purpose, but not of limitation, as I desire it to be understood that the principles of the invention may be embodied in many other forms and used in many other ways than herein shown, without losing its spirit or essence. In the embodiment here illustrated, the paper fastening tool is shown as an implement similar in form to a pair of pliers, consisting of two levers, 1 and 2, pivoted together by a pintle 3, and having long arms or handle portions 4, 5, and the short arms or jaws 6, 7, respectively. On the jaw 6 is formed a die 8, with which coöperates a punch 9 on the other jaw. The cutting edges on the end of the punch next to the jaw 6 have the form in general of the letter U, and the die is so shaped as to admit the punch, embracing its U-formed edges closely, but being open on the side of the punch opposite to the bottom of the U, so that the punch may cut out a tongue which is integrally united at one end of the paper, instead of being severed therefrom. To express the idea in other words it may be said that the die has a cutting edge 10, which coöperates with the edge or corner 11 of the punch to form the bottom of the U, and the two side edges 12 coöperate with the side edges 13 of the punch to form the legs or sides of the U-shaped tongue. When the sheets of paper represented at 14 are laid on the jaw 6 and the jaws are pressed together, the punch passes into the die, severing three sides of the tongue from the body of the paper and bending up the tongue about the neck whereon it is joined with the body of the paper. In order that this action may take place the die is formed as a slot 15 in the jaw 6, of greater length than the punch, one end and the sides of which slot form shearing edges complementary to the edges of the punch. Also carried by the jaw 7 and projecting therefrom in a direction generally parallel to the punch is a piercing device 16 which passes through the slot 15 near the opposite end thereof from the cutting edge 10 and forms a narrow slot in the paper. Secured to the jaw 6 is a spring guard 17 having an opening 18 to permit the punch to pass through it, and a second opening 19 to receive the piercer. At the end of the opening 18 the guard has a cross-bar 20. The spring guard is secured to the jaw 6 by any suitable means such as a screw 21, and is separated from the jaw by a space sufficient to permit insertion of the paper. The function of this guard is to strip the paper from the punch and piercer after the latter have passed through the paper and when the jaws are separated. The punch in passing into the die and through the sheets of paper cuts the latter on the lines a, b and c shown in Fig. 3, thereby forming a tongue 22, and at the same time bends up such tongue at right angles to the sheet. At the same time the piercing device 16 penetrates the sheets and forms a slot d therein.

The punch is preferably open in its interior and contains one end of a tongue bender 23, which is pivoted to the jaw 7 on a pin 24. When the jaws are closed together 5 the tongue bender 23 strikes the cross member 20 of the guard 17, and is thereby swung about its pivot toward the piercer. In thus moving it engages the tongue 22 of the paper which was previously bent up by the movement of the punch through the die, and 10 lays the tongue back on the paper, pushing its end through the opening or eye 25 of the piercer. Then, when the piercer withdraws from the paper it pulls the tongue 15 through the slot d. It should be noted that the piercer is in the form of a blade, the cutting edge of which is inclined or V-shaped, and the center of which is perforated to form an opening or eye 25 of at 20 least as great a width as the tongue. Thereby, when the tongue is passed through the eye by the tongue bender, it is acted on by the solid material at the end of the piercing blade and withdrawn through the slot d with 25 the effect shown in Figs. 3 and 4, being the same as though the tongue had been bent back against the sheet and tucked through the slot.

In order that the tongue bender may act 30 in the manner described, it is so mounted as to extend from its pivot on an inclination to the path in which it approaches the other jaw, so that the portion 20 of the spring guard has a cam action upon it. Likewise 35 the punch is open in its interior and forward side to give free play to the tongue bender.

After the tongue bender has been displaced as described, and as shown in Fig. 2, 40 it is necessary to restore it to the normal position shown in Fig. 1, and for this purpose I provide a returning lever 26 which has an arm 27 engaging an arm 28 of the tongue bender. This replacer has a second 45 arm which passes through an opening 29 in the jaw 6 and the end of which is bent over to make a hook 30. The engagement of this returning lever with the jaw 6 when the jaws are open, causes it to be oscillated about 50 its pivot 31 into the position shown in Fig. 1, whereby its arm 27 bears on the arm 28 of the tongue bender and positions the latter. The hook 30 also acts as a stop to prevent too wide separation of the jaws when 55 the implement is open.

The arms of the paper fastening implement are spring-opened and the form of the spring by which the opening is effected, providing as it does great stiffness, with sufficient resiliency to permit a long life, is an 60 important feature of the invention. The spring has two end portions 32 and 33 which bear against the arms or handles 4 and 5 respectively, and an intermediate portion 34 65 in the form of a figure 8. The pindle 3 of

the implement passes through one of the loops of the figure 8, the ends 32 and 33 of the spring passing to opposite sides of the loop. This form of spring permits sufficient range of movement of the arms of the implement for the desired purpose, without being in itself subjected to any great bending strains, since its length is so great that it is not flexed through a very large angle during the opening and closing of the jaws. 70 By following the direction of the spring from one end to the other, as for instance from the end 32, it will be seen that it extends in the direction of the handle 4 to the pivot, being bent back around the latter and 80 extending in almost the opposite direction, then being bent in a reverse curve and brought around the pindle a second time in the same direction of curvature as at first, until its other end bears against the handle 85 5. The spring thus has a sinuous form with two of its loops overlapping.

I claim,—

1. A paper fastening implement comprising pivotally connected arms, a punch and a slitter carried by one of said arms, a die carried by the other arm, a folder pivotally mounted upon the punch arm, means whereby the arms may be brought together for forming a tongue and slit within the paper, 95 the said folder adapted to bend the tongue into engagement with the slitter whereby the slitter upon its return movement will draw the tongue through the slit within the paper, and a returning lever for returning 100 the folder to its normal position.

2. An implement for fastening paper comprising a co-operating punch and die formed to cut a tongue in the paper, a slitter, a tucker for bending the tongue toward the 105 slitter, the slitter having a tongue engaging part whereby it is adapted to draw the tongue through an adjacent part of the paper, and a returning lever for returning the tucker to its normal position.

3. A paper fastening implement comprising a pair of arms adapted to be forced together, a die formed within one of said arms, a punch carried by one of said arms, a piercing device carried by the last mentioned arm, a folder, said punch co-operating with the die when the arms are brought together to form a tongue within the paper, said piercing device adapted to form a slit in the paper adjacent to the 115 tongue, said folder adapted to force the tongue into engagement with the piercing device when the arms are brought together, whereby the piercing device will pull the tongue through the slit formed within the 120 paper, and a returning lever co-operating with said folder for returning the same into its normal position when the arms have been forced apart.

4. A paper fastening device comprising a 130

cutter constructed to form a tongue in the paper, a piercing device adjacent to said cutter and arranged to pass through the paper at the same time with the cutter, said 5 piercing device having an eye, a folder operative while said cutter and piercing device are in the paper for bending back the tongue and passing the same through the eye whereby when the piercing device withdraws it 10 will pull the end of the tongue through the opening which it had previously made, and a returning lever adapted to coöperate with said folder for returning the folder to its normal position after the paper has been 15 fastened.

5. A paper fastening device comprising two coöperating jaws, a die carried by one of said jaws, a punch and a piercing device carried by the other of said jaws, a folder 20 pivotally mounted upon one of said jaws, the said punch adapted to form a tongue within the paper, and said piercing device to form a slit within the paper when the jaws are brought together, said folder 25 adapted to force the tongue backward into an eye formed within the piercing device whereby upon the separation of the jaws,

the piercing device will draw the tongue through the slit formed within the paper, a returning lever pivotally mounted upon 30 one of said jaws, an arm extending from said lever adapted to coöperate with said folder whereby when the jaws are open the folder will be returned to its normal position. 35

6. In a paper fastening device comprising a pair of coöperating jaws, a die formed within one of said jaws, a cutting element carried by the other said jaw, a folder pivotally mounted upon the last mentioned jaw, 40 an arm carried by said folder, a returning lever pivotally mounted upon the cutting jaw, an arm extending from said lever and coöoperating with the arm of the folder, and the said returning lever coöperating with 45 the die supporting jaw whereby the folder will return to its normal position, substantially as and for the purpose specified.

In testimony whereof I have affixed my signature, in presence of two witnesses.

DANIEL W. GAGE.
